UNITED STATES PATENT OFFICE

ALEXANDER W. KEEMA, OF WOONSOCKET, RHODE ISLAND

COMPRESSOR CYLINDER

Application filed October 23, 1929. Serial No. 401,942.

My present invention relates to refrigeration systems, and has particular reference to improvements in gas compressors therefor.

One object of my invention is to provide a port construction facilitating the rapid admission of the refrigerating gas to the compressor cylinder.

Another object of the invention is to utilize a piston-controlled admission port for providing free communication between the crank case and the cylinder when the piston is at the inner end of its stroke.

A further object is to provide a piston controlled admission port of large area which is formed to permit free passage of the piston rings.

With these and other objects and advantageous features in view, the invention consists of novel arrangements of parts more fully disclosed in the detailed description following, in conjunction with the accompanying drawings, and more particularly set forth in the appended claims.

In the drawings:

Fig. 1 is an elevation of a refrigerating system including the novel compressor;

Fig. 2 is a sectional elevation of the compressor;

Fig. 3 is a perspective view, partly in section, of a portion of the compressor cylinder, showing the admission port; and

Fig. 4 is a section of the cylinder on the line 4-4 of Figure 2, showing the communication grooves.

It has been found desirable in the practical operation of compressors of the reciprocating type suitable for refrigeration apparatus, to provide an annular sinuous gas admission groove about the inner surface of the cylinder to be uncovered by the piston when at the inner end of its stroke. This construction presents a large inlet port area and facilitates rapid admission of the refrigerating gas to the compression cylinder, while at the same time permitting the piston rings to freely pass by without catching in the groove. Also, it is found of advantage from a practical standpoint to groove the side walls of the cylinder to provide communicating passages between the crank case and the admission port.

sion port; and the following is a detailed description of the present embodiment of my invention showing one arrangement of annular groove by which these advantageous results may be accomplished.

Referring to the drawings, the refrigeration system diagrammatically indicated in Figure 1 includes the compressor C, the condenser K, the expansion nozzle N, and the evaporator E, the refrigerating fluid being compressed in the compressor, liquefied in the condenser, and vaporized in the expansion nozzle and evaporator to absorb heat. The compressor includes a crank case 10 in which the drive shaft 11 is rotatably mounted and on which is operatively mounted the piston drive cam 12. The cylinder 13 is mounted on the crank case in communication therewith, the upper end being closed by the valve plate 14 and cylinder head 15. In the cylinder is mounted the reciprocating piston 16 operatively connected to the cam 12 by the connecting rod 17 and the cam yoke 18.

The gas inlet pipe 19 leads the heated low pressure refrigerating gas to the crank case; vertical grooves 20 of ample area are provided in the cylinder wall on opposite sides thereof for communicating the crank case with the cylinder admission port 21, formed as an annular sinuous channel or groove which may be serpentine or zigzag, as best shown in Figure 3. The port 21 is located so as to be substantially uncovered by the piston when at the inner end of its stroke; by forming of this port in a zigzag or serpentine path it is found that the piston rings 22 will readily slide thereover without catching in the edges of the groove, the port being of sufficient area to quickly admit a large volume of gas into the cylinder from the crank case.

After the low pressure gas has entered into the cylinder the piston 16 is forced upwardly to compress the gas in the upper portion of the cylinder to a predetermined pressure which will lift the discharge check valve 23 against the pressure of its adjustable spring 24 to permit passage of the compressed gas through the discharge port 25 into the cylinder head 15. The compressed gas now passes

through conduit 26 into the conduit 27 leading to the expansion nozzle, a top line valve 28 being positioned in the cylinder head and normally seating therein to seal the system, but being movable to cut off the discharge line and permit purging of the system.

A novel shaft sealing structure is provided to effectively resiliently seal the compressor shaft, and at the same time act as a vent for relieving abnormal pressure without loss of refrigerating liquid. The crank case has a thrust bearing 29 for the shaft 11 at one end, and a bearing 30 at the other end, the bearing 30 having passages 31 communicating with the crank case and the cylindrical sealing chamber 32. The shaft has a hardened sealing face 33 thereon, contacted by a sealing ring 34 joined by a metallic bellows 35 with a lock ring 36 locked against the end of the sealing chamber, with the usual metal gasket therebetween, by a lock cap 37 which screw threadedly engages the exterior of the sealing chamber.

A spring 38, preferably rectangular in cross section, engages the sealing ring 34 to resiliently press the sealing ring against the sealing face 33, an adjusting bushing 39 concentric with the end of the shaft 11 screw threadedly engaging a correspondingly screw threaded opening in the cap 37 to be movable for regulating the tension of the spring 38. The bushing 39 has recesses 40 which are engageable by the head 41 of a lock screw 42 to lock the bushing in adjusted position. In adjusting, the bushing is screwed up to fully compress the spring, and is then backed to permit a slight movement of the spring sufficient to vent gas, but not fluid.

The novel construction of the compressor cylinder and the admission port permits an immediate filling of the cylinder as soon as the admission port is uncovered, while at the same time preventing engagement of the piston rings with the edges of the port groove.

While I have described a specific structural arrangement of the cylinder and the cylinder port, such changes as appear desirable to suit different compressor requirements may obviously be made, within the spirit and the scope of the invention as defined in the appended claims.

I claim:

1. In a compressor, a crank case, a cylinder supported thereon, a piston mounted to reciprocate in the cylinder, the cylinder wall having a sinuous groove therein positioned to be uncovered by the piston when at the inner end of its stroke, and a passageway providing a communication between the crank case and said groove.

2. In a compressor, a crank case, a cylinder mounted thereon, a piston mounted to reciprocate in the cylinder, the cylinder wall having a zigzag groove therein positioned to be substantially uncovered by the piston

when at the bottom of its stroke, and a groove formed lengthwise in the surface of the cylinder providing a gas passageway from the crank case to the cylinder through said zigzag groove.

3. In a compressor, a crank case, a cylinder mounted thereon, a piston mounted to reciprocate in said cylinder, the cylinder wall having a circumferential groove therein at a point above the position of the piston when at the bottom of its stroke, and a fluid conduit communicating with said groove for inlet of fluid thereto.

4. In a compressor, a crank case, a cylinder supported thereon, a piston mounted to reciprocate in the cylinder, the cylinder wall having an annular groove positioned to be uncovered by the piston when at the inner end of its stroke, and a passageway providing a communication between the crank case and said groove.

5. In a compressor, a crank case, a cylinder supported thereon, a piston mounted to reciprocate in the cylinder, the cylinder wall having an annular groove with laterally displaced portions and positioned to be uncovered by the piston when at the inner end of its stroke, and a passageway providing a communication between the crank case and said groove.

6. In a compressor, a crank case, a cylinder mounted thereon, a piston mounted to reciprocate in said cylinder, the cylinder wall having a groove with a longitudinal and a transverse portion and open at its lower end to said crank case and at its upper end to the cylinder at a point above the position of the piston when at the bottom of its stroke.

In testimony whereof I affix my signature.

ALEXANDER W. KEEMA.
